UNITED STATES PATENT OFFICE.

JOHN S. MATSON, OF GREENVILLE, PENNSYLVANIA.

RAILWAY BLOCK SYSTEM.

SPECIFICATION forming part of Letters Patent No. 699,542, dated May 6, 1902.

Application filed January 13, 1902. Serial No. 89,466. (No model.)

To all whom it may concern:

Be it known that I, JOHN S. MATSON, of Greenville, Mercer county, Pennsylvania, have invented a new and useful Railway 5 Block System, of which the following is a full, clear, and exact description, reference being had to the accompanying drawings, forming part of this specification, in which—

Figure 1 is a perspective view showing a 10 single-track railroad provided with my improved system. Fig. 2 is a diagrammatic plan view of the same; and Fig. 3 is a view similar to Fig. 2, showing a similar form of the system.

15 My invention relates to a block system for railroads, such as steam or electric roads, and more especially to single-track systems, and it is designed to provide a block system which will do away with time-tables and the 20 classification of trains, also the necessity for telegraphic train-orders, do away with the delay incident to such orders, and avoid a misunderstanding and prevent collisions upon the system.

25 In the drawings, referring to Figs. 1 and 2, in which I show the preferred form of my invention, 2 represents a single-track railroad having at the block-station lap-sidings 3 3, extending from the block-station on opposite 30 sides of the track. At the outlet or clearance to the end of each of these sidings a switch 4 of ordinary form is located, which is connected to operating mechanism in the single tower 5. Each of these switches is also provided with hand or electric operating mechanism 6 in connection with the usual switch-stand. The signal-tower also contains mechanism for controlling the switches at the entrance end of the sidings.

40 At the block-stations are provided two semaphore-signals 77, each having two blades 8 and 9 extending to the right of approaching trains, the upper blade governing trains on the main track and the lower blade governing 45 the corresponding siding. The blades upon one semaphore extend in the opposite direction to those upon the other, one set governing the trains coming in the opposite direction from that governed by the other semaphore. Each blade is provided with the usual 50 green and red-lights for use at night, the

horizontal position of a blade or a red signal indicating "danger," while perpendicular position or green light indicates "clear."

In the clearance position of each siding is 55 placed a derail 10, having a dwarf-signal 11 to indicate its position. When the small arm of the dwarf-signal is in a horizontal position or shows a white light at night, it indicates that the derail-switch is open and the train 60 must be stopped before passing it. When this arm is perpendicular or shows a green light at night, it indicates that the derail is closed, main-track switch open, and the train can proceed. These derails are also operated 65 from the signal-tower at the block-station.

In the operation of the system the train approaching the block-station from either direction is governed by the semaphore-signals. All trains must approach under full control, 70 prepared to stop before passing the semaphore-signals when they indicate "danger." The lower blade of the semaphore for this train, if in a horizontal position, indicates that the switch is open for the siding. The 75 train then takes the siding, clearing the main track, passing the red signals. When the lower blade is perpendicular or shows a green light at night and the upper blade is horizontal or shows a red light at night, the train 80 will stop before passing the signal and hold the main track until the upper blade indicates "clear." After the train has entered the siding and cleared the main track it is governed by the dwarf-signal at the derail 85 near the opposite end of the siding, and when a train has been side-tracked and afterward receives a clear position of the dwarf-signal it will proceed to the next block-station, whether any train has passed or not, the same 90 as though the main-track signal had been received at the block-station. When it is necessary for a train to back out of a siding at a block-station, it will be governed by the main-track block-signal after it has returned 95 to the main track.

In the form of Fig. 3 there is only one siding 3 at the block-station, this siding having a derail 10 near its clearance at the opposite end from the block-station, the semaphore-signal 7 on this side having the two blades, 100 as in the first form. The main track 2 is also

provided with a derail 10 near the end of the siding next to the block-station, and the semaphore upon this side has but one arm to indicate "clear" or "danger." In this form whenever the one-arm semaphore indicates "danger" trains will stop before passing a derail in the main track and remain until a "clear-signal" is given. If a train is to be met or passed, the operator will run it through the siding, opening both ends of the siding before arrival of the expected train. After a train has been stopped in this form if conditions are such that markers on the rear of the train cannot be seen by the operator at the block-station the block must not be cleared until the conductor reports his train "clear" between the switches. Such trains must observe the position of the dwarf-signal at the clearance before attempting to start, as the one-arm block-signal may be intended for a train passing through the siding going in the same direction.

In cases where the main track is obstructed block operators will run trains through sidings. Any train finding the switch of a passing siding open at the opposite end of the siding from the block-station will not stop, but proceed to the block-station upon the siding and be governed by the main-track block-signal at the block-station.

The engineman when approaching block-stations calls for changing the signals from "danger" to "clear," and when he receives this signal the train may proceed to the next block-station regardless of any train.

It will be seen that the advantages of my invention result from the use of two derails in connection with signals for indicating the condition of the main track and the siding or sidings. Trains are governed by block-signals, and after stopping there is no waiting for orders to be obtained at the tower. A large amount of time is thus saved, preventing delays to the trains, reducing the force at the despatcher's office, and preventing collisions. The liability to misunderstanding of orders, which is a frequent cause of collisions, causing loss to life, is done away with. One train has no more rights than another. Trains never die or outlaw. They re-

tain the same identity from start to finish—i. e., extra.

Changes may be made in the form and arrangement of the sidings, the derails, signals, &c., without departing from my invention. 55

I claim—

1. In a railway block system, a block-station having at least one siding, a derail in the siding, and semaphore-signals for the siding and main track; substantially as described. 60

2. In a railway block system, a block-station having a siding, a derail near the clearance of the siding, and provided with a signal, and semaphore-signals upon opposite sides of the track at the entrance end of the 65 siding; substantially as described.

3. In a railway block system, a block-station having an operating-tower, a siding having a derail with a signal, semaphore-signals for the main track and siding, and connections leading from the switches, derail and signals to the tower; substantially as described. 70

4. In a railway block system, a block-station having at least one siding, two derails 75 located in the tracks adjacent to the station and having signals, semaphore-signals for the main track and sidings, and connections leading from the switches derails and signals to the block-station tower; substantially as described. 80

5. In a railway block system, a block-station having two lap-sidings, a derail in each siding provided with a signal, and semaphore-signals for the sidings and main track; substantially as described. 85

6. In a railway block system, a block-station having an operating-tower, two lap-sidings, a derail on each siding, semaphore-signals for the sidings and main track, and 90 mechanism in the tower for operating the switches, derails and signals; substantially as described.

In testimony whereof I have hereunto set my hand.

JOHN S. MATSON.
